UNITED STATES PATENT OFFICE

WILBUR L. TYRELL, OF AUDUBON, NEW JERSEY, ASSIGNOR, BY MESNE ASSIGNMENTS, TO RADIO CORPORATION OF AMERICA, OF NEW YORK, N. Y., A CORPORATION OF DELAWARE

DIAPHRAGM

Application filed June 14, 1928. Serial No. 285,462.

My invention relates to a diaphragm for acoustical purposes.

In accordance with my invention, a member or section of diaphragm-forming material is so corrugated that the contour of said member or section is substantially unaltered with resultant increase in mechanical strength and improvement in acoustic qualities.

10 Further in accordance with my invention, a member or section of diaphragm-forming material is corrugated to a degree usually numerically exceeding 100 corrugations per square inch for the useful purpose aforesaid.

15 Further in accordance with my invention, either before, while, or after a member is brought to diaphragm-forming configuration, a surface or face thereof is so corrugated that the contour of said member is substantially unaltered.

20 More particularly in accordance with my invention, the aforesaid corrugating operation is performed simultaneously with a diaphragm-forming operation, such, for example, as a die shaping operation including, as a feature, the interposition of a sheet of fabric between one die and a face of the diaphragm-forming member.

25 My invention resides in the novel diaphragm and in the novel method of producing the same as hereinafter described and claimed.

30 For an illustration of some of the forms my diaphragm may take and for an understanding of my method, reference is to be had to the accompanying drawings in which:

Figure 1 is a plan view of a diaphragm constructed in accordance with my invention.

35 Fig. 2 is a vertical sectional view of the diaphragm shown in Fig. 1.

Fig. 3 is a plan view of another form of diaphragm constructed in accordance with my invention.

40 Fig. 4 is a vertical sectional view of the diaphragm shown in Fig. 3.

Fig. 5 is a side elevational view of the diaphragm shown in Figs. 3 and 4 and having an actuating member projecting therefrom and secured thereto.

45 Fig. 6 is an enlarged sectional view show-

ing a diaphragm and the corrugating structures on opposite sides thereof.

Fig. 7 is a vertical sectional view of a die structure and associated corrugation-forming members.

55 In each of Figs. 2, 4, 5 and 7 the diaphragm is shown as having a thickness much greater than the actual thickness of the material from which the diaphragm is usually constructed. Hence, said Figs. 2, 4, 5 and 7 do not represent the corrugations with entire accuracy. In Fig. 6, the various dimensions are more nearly proportionately correct and, therefore, this view substantially correctly illustrates one form of diaphragm after it has 60 been corrugated in accordance with my invention.

65 Referring to Figs. 1 and 2, there is illustrated a diaphragm D of circular configuration and comprising, when looking at one face thereof, a centrally disposed depression 1 and a plurality of channels 2 concentrically disposed with respect to the diaphragm center. In the example illustrated, diaphragm D comprises two of the aforesaid channels 2 70 while outwardly of the outermost channel 2 75 said diaphragm D comprises a circular corrugated section 3 bordered by a plane section 4.

70 A diaphragm of the character described above is usually, although not necessarily, formed by a die shaping operation, the wall structure of the depression 1 and channels 2 forming major corrugations concentrically disposed with respect to the diaphragm center. The alternate ridges and depressions comprised in the diaphragm section 3 also constitute major corrugations which extend tangentially with respect to a circle having the center of the diaphragm D as its center. 80

85 The aforesaid major corrugations in the diaphragm D improve its acoustic properties and their utilization is desirable when the diaphragm is comprised in the sound box of a talking machine, phonograph, or the like. 90

95 In accordance with my invention, to further enhance or improve the acoustic performance of the diaphragm D, it is provided on one or both faces thereof, as illustrated, with a plurality of minor indentations and 100

projections such as corrugations or the like that are minor in size in contradistinction to the aforesaid major corrugations.

Referring to Figs. 3 and 4, there is illustrated another diaphragm D1 constructed in accordance with my invention. This diaphragm comprises a substantially plane outer section 5 surrounding an inner corrugated section 6, the corrugations of the section 6 extending tangentially with respect to a circle having its center at the center of the diaphragm D1. The corrugated section 6 merges into a conical section 7, angularly related with respect to the plane of the section 5. Conical section 7 is angularly related to a section 8 preferably forming a part of the surface of a sphere, said section 8 merging into a conical section 9, preferably rounded at its apex.

The portion of the above described diaphragm D1 within the corrugated section 6 may aptly be designated as the "plunger portion" and, in accordance with my invention, it is highly desirable that said plunger portion, on one or both faces, be provided with minor indentations, the latter, as was the case with the diaphragm illustrated in Figs. 1 and 2, contributing to a marked extent to the acoustic efficiency of the diaphragm.

A diaphragm of the character illustrated in Figs. 1 and 2, as well understood in the art, may be connected by a spider or the like, not shown, to some vibrating member, for example, a talking machine or phonograph needle, or the armature of a loud speaker. With such a construction, the driving connection for the diaphragm is distributed over a substantial area of one face thereof.

On the other hand with a diaphragm construction such as illustrated in Figs. 3 and 4, the diaphragm is driven or operated by a member connected thereto only at its center, such, for example, as illustrated in Fig. 5, where the diaphragm D1 has a member 10 soldered or otherwise suitably secured thereto only at its mid-point, said member 10 terminating in a stylus bar 11 which comprises the usual threaded member 12 for maintaining a phonograph needle, not shown, in assembled relation therewith.

As stated above, the member or material from which the diaphragm is to be formed may be provided with the herein-described minor corrugations at any suitable time either before, while, or after the member is brought to diaphragm-forming configuration. Preferably, however, when the diaphragm is formed by a die shaping operation, the minor corrugations are formed on one or both faces thereof during the last stage shaping operation.

For such last stage operation there may be utilized a die structure of the character illustrated in Fig. 7, said die structure comprising a female die F and a cooperating male die M, said dies being shaped to bring the dia-

phragm to suitable configuration such, for example, as illustrated in Fig. 4. Disposed between one of the faces of the diaphragm D1 and one of the dies, for example, the female die F is a sheet R of yielding material such, for example, as soft rubber. With this arrangement, there is disposed between the other face of diaphragm D1 and the male die M a member or sheet of material S suitable for forming the aforesaid minor corrugations in the diaphragm D1. The member S may be any one of a number of suitable materials, for example, finely meshed wire screen, cloth, muslin or burlap.

It is desirable that diaphragms utilizable as herein described be formed from suitable sheet material such, for example, as an aluminum alloy of the type known to the trade as 3-S. O. having a thickness of the order of 0.002 of an inch, more or less. Material of this character may be readily deformed or shaped and is inherently capable of retaining a set formation. Accordingly, upon relative movement of the dies M and F toward each other, the diaphragm D1 receives not only the configuration imposed by said dies but is provided with minor indentations due to the presence of the sheet fabric S. The provision of a rubber sheet R, when the diaphragm is of suitable thinness, permits slight bodily movement of adjacent small portions of the diaphragm so that the aforesaid minor indentations appear on both sides of the diaphragm, a depression on one side being opposite a raised portion on the other side, Fig. 6. Obviously, in lieu of the constructions illustrated, the rubber sheet R may be omitted and sheets of fabric or the like, disposed on opposite sides of the diaphragm, each sheet of fabric, then, functioning as a corrugating member.

Essentially, my invention involves the provision, on one or both faces of the diaphragm, of the above described minor indentations over any desired area thereof but preferably only within the aforesaid tangential corrugations and arranged, preferably, in regular or symmetrical order. The minor corrugations on one face of the diaphragm may vary greatly in number, and ordinarily are of such small dimensions that the contour of the diaphragm is only slightly altered. Thus, for example, inwardly of the above described plunger portion there may be provided substantially 50 corrugations per square inch, more or less, although usually it is desirable that their number be much greater, such, for example, as 600 per square inch, or more. When thus corrugated, the diaphragm is mechanically strengthened and, as a result, its acoustic properties are improved. In this sense, it has been shown, by experience and tests, that an increase is effected in the volume of the sound reproduction while at the same time, any undue tendency of the diaphragm,

in different regions thereof, to respond to particular frequencies is decreased or suppressed.

I claim as my invention:

- 5 1. A diaphragm comprising a peripheral section, and a plurality of sections angularly disposed with respect to said peripheral section, said second named sections being provided with a plurality of minor indentations and projections, said indentations and projections being of relatively small dimensions so that the contour of said sections is substantially unaltered.
- 10 2. A diaphragm comprising a section of an aluminum alloy having a thickness of the order of 0.002 of an inch and having an indented surface, the indentations in said surface being of relatively small dimensions so that the contour of said diaphragm section is substantially unaltered.
- 15 3. A diaphragm comprising a section of an aluminum alloy having a thickness of the order of 0.002 of an inch and having an indented surface, the indentations in said surface numerically exceeding one hundred per square inch.
- 20 4. A diaphragm comprising a corrugated peripheral portion, and a central plunger portion having a plurality of concentric annular portions of predetermined configuration, said annular portions having minor indentations and projections formed on their surfaces without substantial deformation of said annular portions from their predetermined configuration.
- 25 5. A diaphragm of thin sheet metal having a plurality of concentric annular portions of conical configuration, said portions having minor surface indentations and projections formed on their surfaces without substantial deformation of said annular portions.
- 30 6. A diaphragm of thin sheet metal having a plurality of concentric annular portions of conical configuration, said portions being provided with minor surface indentations numerically exceeding one hundred per square inch without deforming said annular portions.

In testimony whereof I have signed this specification this 12th day of June, 1928.

WILBUR L. TYRRELL.
